UNITED STATES PATENT OFFICE

2,123,103

ELECTRICAL CONNECTER

Milton O. Fischel, Du Bois, Pa.

Application May 17, 1937, Serial No. 143,181

3 Claims. (Cl. 173—324)

This invention relates to an improved swivel connector for electric cords used on various electrical appliances such as toasters, electric sad-
5 irons, lamps and similar appliances, where the cord is apt to get twisted or entangled, and the purpose of the connector is to permit the appli-
ance to be freely moved continuously in a circle in either direction without twisting or entangling the wires connecting same to a source of current.

10 Another purpose of the invention is to construct a connector of the type indicated which may be readily assembled and which is composed of a relatively small number of simple parts or elements.

15 The connector constituting the instant invention is particularly adaptable for floor, table or other styles of lamps to enable the light from the lamp to be directed in any direction within a complete circle, with the socket and bulb of the 20 lamp turnable in either direction in the plane of said circle. It will be understood, however, that the improved connector can find utility for other purposes as indicated above.

The above and other aims and purposes will be 25 apparent from the detailed description herein-
after appearing when taken in conjunction with the appended drawings forming a part thereof and showing preferred embodiments of the invention and in which:—

30 Fig. 1 is a side elevational view of a lamp with the invention applied thereto, and showing in dotted lines the position an electric socket, bulb and shade may assume when swung about the axis of the novel connector.

35 Fig. 2 is a perspective view of the connector in assembled operative condition with respect to an electric lamp socket, but with a portion of the connector housing removed.

40 Fig. 3 is a view partly in elevation and partly in section of the connector shown in Fig. 2.

Fig. 4 is an exploded perspective view of the 45 connector of Fig. 2, showing the various elements constituting same and prior to the assembly of said elements into operative position.

Fig. 5 is a view similar to Fig. 1 of another type of lamp embodying a modified form of the invention.

Fig. 6 is a view partly in elevation and partly in section of the modified form of the invention.

50 Fig. 7 is a sectional view taken on lines 7—7 of Fig. 6, and

Fig. 8 is an exploded perspective view, similar to Fig. 4, but of the modification shown in Figs. 5 to 7 inclusive.

55 Referring first to the form of the invention

shown in Figs. 1 to 4 inclusive of the drawings, and particularly to Fig. 1, the reference character L represents a table lamp, characterized by a base B rigidly supporting a standard S having a lower horizontal portion or arm 10, two similar converging arms 11, 11^a and an upper smaller arm 12 on which the novel connector generally designated as C is mounted. The lamp L embodies a shade S provided with an electric bulb socket 15. The dotted lines in Fig. 1 of the drawings illustrate the position the shade S and socket 15 may assume, that is, it may be swung in a circle either backwards or forwards on the axis of the rod or arm 12. An electrical current conducting cord 16^b passes through the base B, the 10 right hand portion of the lower horizontal arm 10, through the converging arm 11, the right hand portion of the upper arm 12 to the connector C to which it is secured in a manner to be shortly described.

20 The connector C proper shown in Figs. 2, 3 and 4 of the drawings embodies a casing or housing H formed of two dissimilar parts or halves. One of the halves is designated as 16, a portion of the other half shown in section at 17 being secured to 25 the half 16 by screws 18 and 19 or the like. It will be understood that this construction provides a fully enclosed housing for the various elements of the connector C. The housing half 16 is characterized by a base wall 20^b and two similar side 30 walls 20, 20^a and horizontal wall portions 21, 21^a, the latter being provided with threaded apertures 22, 22^a for receiving the screws or the like 18 and 19.

A plate 23 of insulating material is positioned 35 internally of the housing half 16 flush with the base wall 20^b being secured thereto by means of screws 24. The base wall 20^b has a large circular opening 25 through which the insulating plate 23 is exposed, said plate being provided with a pair 40 of apertures 26, 26^a. Secured to said base wall 20^b externally thereof is a metal ring 27 having its circular rim portion 28 extending through and bent back to engage the internal edges of the base plate or wall 20^b defining the opening 25 thereon, 45 said rim portion 28 being bent back as at 29 to be clamped between the insulating plate and base wall to firmly mount the ring 27 on said base wall.

The main portion 30 of the conventional lamp socket 15 fits into the ring 27, being frictionally 50 and detachably held therein by means of co-
operating notches or by a set screw or in any other convenient manner.

By referring to Fig. 4, it will be seen that the 55 elements of the connector C comprise two similar

hollow metallic tubes 31, 31^a, each tube being externally threaded at one end thereof, as at 32, 32^a and each having an aperture 33, 33^a at its opposite end. Each of side walls 20, 20^a of the 5 housing H is provided with an opening 34 or 34^a and positioned internally of the casing half 16 is a hollow sleeve 35 of insulating material, said sleeve having apertures 36 and 37^a adjacent its outer edges and an intermediate aperture 38^a. A 10 pair of spaced metallic conductor rings 37 and 38 frictionally embrace and are securely fixed to the external surface of the hollow insulating sleeve 35, the ring 37 having a lateral projection 39 provided with a set screw forming a terminal 40 and 15 the ring 38 having a similar integral projection 41 provided with a set screw 42.

In assembling the swivel connector C the tubes 31 and 31^a and the insulating hollow sleeve 35, which is of a length approximately equal to the 20 distance between the internal surfaces of the housing walls 20 and 20^a, is inserted within the casing half 16, washers 43 and 44 serving to space the sleeve from said walls. The sleeve 35 is placed in alignment with the apertures 34 and 34^a 25 through which are now inserted the metallic tubes 31 and 31^a, said tubes being rigidly secured to opposite ends, respectively, of the insulating sleeve 35 by means of set screws 43^a, 44^a screwed into the respective threaded apertures 33, 36, and 33^a, 30 37^a.

The socket 30 is provided with a pair of contact strips or plug-in blades 50 and 51 which pass through apertures 26 and 26^a in the fiber or insulating plate 23 to contact and ride on rings 37 35 and 38, respectively. The lead or current conducting wire 16^b is passed through the metallic tube 31^a, then through hollow insulating sleeve 35, the conductor 16^a of said lead wire being secured to terminal 40 and conductor 16^b to terminal 42.

In mounting the device on arm 12 of the lamp L, Fig. 1, the tube 31^a is rigidly secured to the right hand portion of arm 12 by means of a lock nut or the like 52, and the sleeve 31 to the left hand portion of the arm 12 by a similar lock nut 53. It should be mentioned that the diameter of the openings 34 and 34^a in side walls 20 and 20^a is so chosen that the tubes 31 and 31^a form a firm frictional fit when inserted therethrough.

50 The operation of the device will now be apparent. When it is desired to adjust the shade S carried by the socket 15, this may be accomplished by turning said shade through an entire circle or an arc thereof in either direction. Such an operation will rotate the entire housing H, this causing the plug-in blades 50 and 51 to ride on the surface of rings 37 and 38 to maintain electrical contact therewith. As the tubes 31 and 31^a are rigidly fixed to arm 12 and as insulating sleeve 55 35 is fixed to said tubes, it will be apparent that conductor cord 16^b will not be twisted and that the lamp shade S and its lamp socket may be freely rotated without danger of twisting the cord and its lead-in wires 16^a and 16^b.

60 Referring now to Figs. 5 to 8 inclusive of the drawings, showing a modified form of the invention, the lamp L' is illustrated as comprising a shade S', a vertical hollow standard B', a pair of diverging arms 61 and 61^a connected to the 65 standard at 61^c and a rotatable horizontal arm 62. Lead wire 63^b passes through standard B', arm 61, connector C', the right hand portion of rotatable arm 62 to shade S' and its associated 70 electric bulb and socket (not shown). The reference character D designates a dummy member

similar in design to connector C' for the purpose of maintaining the symmetrical appearance of the lamp, said dummy connector D merely serving as a bearing for the rotatable horizontal arm 62.

5 The conductor C' embodies a housing H' formed of two dissimilar halves 66 and 67, the latter secured to the former by screws 68 and 69, fitting in threaded apertures 72, 72^a in wall portions 71 and 71^a of casing 66. The casing half 66 is provided with a base wall 70 and side walls 75 and 76, said side walls having apertures 78 and 79.

10 The base wall 70 is provided with an opening 80 having threaded therein an externally threaded metallic sleeve 81, lock washer or sleeve elements 15 82 and 83 serving to non-rotatably secure the sleeve 81 to said base wall. Supported on the latter by means of insulating spacer members 84 and 85 and belts and nuts 86 and 87, is an insulating strip 89. The insulation strip 89 has 20 fastened thereto by bolts and nuts 90 and 91 a pair of spaced contact strips 92 and 93 carrying terminals 94 and 95 to which the leads of conductor wire 63^b are secured. By referring to Fig. 8, it will be seen that an insulating sleeve 35 25 having rings 37, 37^a, and sleeves 31 and 31^a are assembled within the casing half 76 in a manner described in the form of the invention of Figs. 1 to 4 inclusive. The metallic tube 31^a, however, in the modified form of the invention is 30 devoid of the threaded end 32^a for a purpose to be shortly mentioned. When assembled the contact strips 92 and 93 ride on rings 37 and 37^a, respectively.

In operation of the device of Figs. 5 to 8 inclusive, the casing H' by means of threaded sleeve 81 is rigidly and non-rotatably secured to the arm 61, a lock-nut or the like 100 being used for this purpose. The horizontal arm 62 is locked to the threaded end 32 of tube 31 by means of a 35 lock-nut or the like 101. Upon rotation of the shade S' the arm 62 will rotate, which in turn will rotate tube 31, insulating sleeve 35 and tube 31^a, the latter functioning as a pintle or rotatable bearing, the contact strips 92, 93 being always 40 in electrical contact with rings 37 and 38, as will be understood. As previously indicated, the dummy connection D merely functions as a bearing 45 for the left-hand portion of arm 62.

50 From the above description, it will be appreciated that there has been provided a novel connector well adapted for its intended function. Furthermore, while the novel electrical connector has been described in detail, yet it will be obvious that various changes and modifications may be 55 made therein which fall within the spirit of the invention and it is intended to cover all such and be limited in this respect only as may be necessary by the scope of the claims hereto appended.

Having thus set forth the invention, what I 60 claim and desire to secure by Letters Patent is:

1. An electrical connector comprising a casing including a base wall provided with a pair of spaced apertures, a bulb socket having a pair of blades, said blades projecting through said apertures, said socket carried by said base wall, an insulated member supported within said casing, said insulated member having a pair of spaced rings carried thereby, said rings contacting said blades, means projecting within and extending 65 beyond said casing secured to said insulated member, said means non-rotatably holding said insulated member within said casing, said casing being movable relatively to said insulated member.

2. An electrical connector comprising a casing including a pair of spaced apertured walls and an apertured base wall connecting same, a hollow tube extending through each of said apertures in said spaced walls, an insulated sleeve within said casing connected to said tubes, a pair of rings carried by said sleeve, a pair of socket plug-in blades extending through the apertures in said base wall and contacting said rings, said tubes having means to rigidly connect same to a lamp support, said casing being rotatable on said tubes as an axis.

3. An electrical connector comprising a casing including a pair of spaced apertured walls and an

apertured base wall connecting same, an insulating plate having a pair of openings secured to said base wall, a lamp socket mounted on said casing having a pair of plug-in blades extending through the openings in said insulating plate, metallic tubes projecting through the apertures in said spaced walls, an insulating sleeve within said casing connecting said tubes, said sleeve having a pair of conductor rings secured thereto with the rings in contact with said blades, said tubes having threaded outer ends for non-rotatable connection to a support, said casing being rotatable about said tubes as an axis.

MILTON O. FISCHEL.
